UNITED STATES PATENT OFFICE.

CHARLES LAWRENCE STOKES, OF LOS ANGELES, CALIFORNIA.

STOP SIGNAL.

Application filed March 11, 1924. Serial No. 698,541.

My invention relates to improvements in stop signals for automobiles wherein the signal will be automatically operated according to the speed of the engine actuating the automobile.

The principal object of my invention is to utilize the engine induction vacuum for operating the stop signal.

A further object of my invention is to actuate the signal automatically according to the degree of engine vacuum which prevails at predetermined speeds of the automobile.

Other objects will become apparent as my invention is more fully disclosed.

15 Referring to the drawings in which the same numbers indicate like parts:

Fig. 1 is a view of my invention operatively connected to an automobile engine.

20 Fig. 2 is a longitudinal view of the stop signal.

Fig. 3 is a detail of part of Fig. 2.

Fig. 4 is a view along the lines A—A of Fig. 2.

25 Fig. 5 is a transverse sectional view along the lines B—B of Fig. 2.

Fig. 6 shows the visual signals given by the apparatus.

An internal combustion engine 1 has an intake manifold 2 to which is attached a carburetor 3. The carburetor 3 has a control valve 4 and, preferably on the engine side of the valve 4, a pipe 5 is attached to the interior of the manifold 2 for applying the engine induction vacuum to the interior of a chamber 6 wherein a piston 22 is slidably placed for reciprocally moving a rack 21. Within the chamber 6 is placed a spring 23 for normally returning the piston 22 to a predetermined position when the application of engine vacuum through the pipe 5 is stopped.

The stop signal itself comprises a barrel or casing 7, which is divided by a partition 10 into two compartments of unequal lengths, the larger of which contains a revolvable cylinder 11 adapted to be moved to different positions depending on the engine vacuum. One end of the barrel 7 is closed by a cap 8 and the other end of the barrel 7 is closed by a cap 9 and after the cylinder 11 has been inserted in the barrel 7, caps 8 and 9 are placed

in position and securely held, with respect to the barrel 7, by a rod 14 which passes through the center of the barrel 7 and the cylinder 11. The cylinder 11 is revolvably held on the rod 14 by collars 12 and 13 and on the collar 13 is fixed a pinion 20, the teeth of which are adapted to mesh with the teeth of rack 21.

The rod 14 is held at one end against the collar 13 by a washer 15 and a pin 16 and at other end is adjustably tightened to hold the signal together by lock-nuts 17 and 18 placed on the inside and outside of cap 8 respectively.

The barrel 7 is preferably made of metallic tubing which is solid circumferentially except as regards a blank portion as illustrated in Fig. 5, which blank portion is placed in a position at the rear of an automobile to be visible to automobiles or vehicles following the same so that the different signals to be shown by the revolving cylinder 11 may be 70 visible therethrough. The cylinder 11 is made of metal with substantially solid ends which are joined together with the strips 33, 36 and 37 thus providing blank spaces 34 and 35 between the strips for the insertion of 75 the required signals and these insertions are generally made of some transparent, or colored, material on which outstanding signs or legends are placed such as are shown in Fig. 6.

In the partition 10 is placed an orifice 38 and in one end of the cylinder 11 is cut a slot 39 in order that a wire 24 may be conducted therethrough from a battery 25 the terminal of which is grounded at 26. The wire 24 is 85 broken by a switch 27 and connected therefrom to a wire 28 which is grounded at 32 and connected to wire 28 in series are two electric light bulbs 29 and 31 placed in the interior of compartment 30 and the cylinder 11 respectively. The compartment 30 is closed by a red glass and the combination of the red glass and the lamp 29 constitutes the tail light of the automobile on which the barrel 7 is mounted but the closing of switch 27 95 lights both the lamps 29 and 31.

The operation is as follows:—

Should the engine 1 be at rest, the position of the cylinder 11 is as shown in Fig. 5 where-in no signal is showing to outside view on ac- 100

count of the metal blank 33 which effectually blinds the opening in the barrel 7. Upon starting the engine 1, and at idling speeds, the highest vacuum will prevail in the manifold 2 and the same is applied through the pipe 5 to the interior of the chamber 6 whereon the piston 22 will be drawn to its inner limit thus causing the rack 21 to revolve the pinion 20 and thereby the cylinder 11. In this manner, 70 and only at the highest vacuums, the cylinder 11 will be revolved to the end that the portion 34, will be revolved to be exhibited through the open port in the barrel 7. This portion 34 contains preferably a celluloid, or 75 mica, transparency on which is superimposed in bright red letters the word "Slo". Upon increase in speed due to the opening of valve 4, the vacuum in the manifold 2 will drop a predetermined amount whereby spring 23 will 80 force the piston 22 on its outward stroke a predetermined distance thus causing the cylinder 11 to revolve a predetermined distance in the opposite direction described. In this manner the spaces 35 are exposed to view 85 through the opening in the barrel 7 at all periods of engine operation except that of the full closure of the valve 4 when the engine 1 is idling. The spaces 35 are preferably closed 90 by a transparency on which a multiplicity of words "Go" are placed in order that the signal "Go" will be shown to the public at all periods of throttle opening except that of the idling position. 95

The speed of the engine 1, and the vehicle 100 which contains the same, is governed by the opening and closing of the valve 4 and at all speeds except that of idling, a greater or less degree of vacuum will prevail in the manifold 2 so that the opening and closing of the valve 105 4 can be so arranged with respect to the inward and outward movement of the piston 22 that the revolving of the cylinder 11 to show different signals will adequately protect the 110 automobile on which the barrel 7 is placed by warning all vehicles following the same. 110

For instance, when the valve 4 is closed for 115 idling conditions, a vacuum of about 22 inches of mercury will prevail in the manifold 2 but on a slight opening of the valve 4, the vacuum in the manifold 2 will drop rapidly to about 18 inches, or less, of mercury. Therefore the space 34, containing the signal "Slo" will be 120 relatively small as compared with the spaces 35 containing the signal "Go". In this manner upon any acceleration, the signal "Go" will be shown and upon any sudden deceleration, the signal "Slo" will be shown 120

Owing to the simplicity of the moving 125 parts and the construction thereof, my apparatus requires substantially no attention after being installed, the same being automatically governed and operated by the speed of the vehicle to which it is attached, the speed being 130 a function of the engine induction vacuum

applied to the chamber 6 from the manifold 2 through the pipe 5. 70

I claim:—

In a motor vehicle provided with an internal combustion engine provided with a throttle, a signal device on said vehicle, said device comprising a casing, a member movably mounted in said casing and containing different legends, and means responsive to the movement of said throttle for displaying the different legends, one class of legends being shown when the suction is below a predetermined minimum and another class of legends being shown when it is above said minimum. 75

Signed at Wilmington, in the county of 80 Los Angeles, and State of California, this 4th day of March, A. D. 1924. 85
